US0D1075458S

(12) **United States Design Patent** (10) **Patent No.:** **US D1,075,458 S**
(45) **Date of Patent:** **** May 20, 2025**

(54) **TERMINAL**

(71) Applicant: **ELECTRO TERMINAL GMBH & CO KG**, Innsbruck (AT)

(72) Inventor: **Armin Eder**, Absam (AT)

(73) Assignee: **ELECTRO TERMINAL GMBH & CO KG**, Innsbruck (AT)

(**) Term: **15 Years**

(21) Appl. No.: **29/849,626**

(22) Filed: **Aug. 12, 2022**

(30) **Foreign Application Priority Data**

Feb. 14, 2022 (EM) 008858070

(51) **LOC (15) Cl.** **13-03**

(57) **CLAIM**

The ornamental design for a terminal, as shown and described.

DESCRIPTION

FIG. 1 is a front view of a terminal showing my new and ornamental design;

FIG. 2 is a rear elevation view thereof;

FIG. 3 is a side elevation view thereof;

FIG. 4 is an opposite side elevation view thereof;

FIG. 5 is a top plan view thereof;

FIG. 6 is a bottom plan view thereof; and,

FIG. 7 is a top perspective view thereof.

The broken lines depict portions of the terminal that form no part of the claimed design.

1 Claim, 2 Drawing Sheets
